TUFT FORMING SEWING MACHINE

Charles L. Pickworth, Auburn, Victoria, Australia

Application June 26, 1945, Serial No. 601,634
In Australia June 28, 1944

3 Claims. (Cl. 112—79)

1

This invention relates to improvements in and connected with tuft-forming sewing machines—that is to say, machines for applying chenille and like decoration to fabrics.

It is already known to employ for this purpose a sewing machine in which the usual shuttle is replaced by a loop forming hook which moves into position at one side of the needle to engage the loop of the yarn when said needle has descended through the fabric whereby, when the needle is retracted, a loop of desired length is left on the hook. Such apparatus also includes means for successively severing the loops on the hook as the operation proceeds, one or more uncut loops being normally retained on the hook to prevent the yarn from being pulled out by the needle.

Now, the general object of the present invention is to provide improvements in tufting apparatus of the aforesaid type whereby advantages in construction and operation are obtained, while one specific object is to provide improved means for successively severing the formed loops.

With these objects in view the invention resides in apparatus comprising a loop holding member, a loop shearing member pivotally connected to said loop holding member and cutting edges on said loop holding and shearing members arranged to coact with a scissors-like action.

The said loop holding member, which preferably constitutes a hook, may be adjustably mounted on a longitudinally disposed rock shaft (which may be the shaft normally used in a sewing machine to carry the shuttle). Alternatively said hook may be independently supported for oscillatory movements and suitably arranged for actuation by said rock shaft or by a rotary shaft. For this purpose the hook may be mounted on a rock shaft provided with an arm which coacts with a cam on the first mentioned rock shaft.

According to a further modification, the loop holding hook is mounted for lateral sliding movements towards and from the needle and is actuated in timed relation with the needle by a cam on the aforesaid rock shaft or on a rotating shaft.

Preferably the said shearing member is guided at a position spaced from the pivotal axis thereof whereby same closes on the loop forming member during each forward movement of the latter.

A salient feature of the invention resides in providing the said shearing member with a shoulder which serves as a stop to prevent the severing of each loop until the succeeding loop is applied to the hook.

Preferably guard means is provided to coact

2

with the needle when the latter is disposed in the vicinity of the lower end of its stroke and ensure that same is correctly located with respect to the hook.

5 Other objects and features of the invention are hereinafter described.

In the drawings:

Figure 1 is a view in end elevation of a sewing machine head incorporating the preferred form 10 of the invention.

Figure 2 is a view in perspective of loop holding and severing means.

Figure 3 is a view in elevation illustrating the operation of the loop holding and severing means.

15 Figure 4 is a view in section and is taken on the line 4—4 of Figure 3.

Figure 5 is a view in sectional elevation and is taken on the line 5—5 of Figure 1.

Figure 6 is a view in perspective of a detail.

20 Figures 7 and 8 are views in end elevation and show modified forms of the invention.

In the several figures of these drawings, the same reference numerals are employed to designate the same or corresponding parts.

25 The machine shown in Figure 1 of the drawings is a modified sewing machine of a well known type having a central rock shaft 10 arranged longitudinally below the base plate 11 and supported therefrom in suitable bearings. The shaft 10 is oscillated in the usual way and in timed relation with the needle spindle 12 from the usual spindle 13 in the head 14 of the machine. The shuttle driver which in a sewing machine is mounted on the rockshaft 10 below the needle spindle, is omitted and in lieu thereof a hook carrying member 15 is clamped to the spindle in such a manner that its angular position may be adjusted.

30 A flat plate 16 (hereinafter termed "the hook plate"), provided at its upper end with an integral lateral arm 16' which terminates in a hook 16" is arranged in a corresponding groove in the outer face of the member 15 and is attached thereto by a screw 17, the screw hole in the plate 16 preferably being slotted to permit of some adjustment of the plate longitudinally of the guide groove. Thus, when the rock shaft 10 is actuated in the usual way, the hook plate is oscillated in its own plane and transversely with respect to the longitudinal axis of the machine, whereby the hook is moved into brushing contact with the outer flattened face of the needle 18 as the latter commences each upward movement from its lowermost position as more fully explained hereinafter.

35 45 50 55 60 65 70 75 80 85 90 95 100

A transversely disposed shear blade 19 in the form of a flat plate is pivotally connected at 20 adjacent one end thereof to the outer side of the hook plate and somewhat below the lateral arm 16' thereon.

A slot 21 extends longitudinally inwards from the opposite end of the shear blade 19 and this slotted end of the blade embraces a guide pin 22 secured to a plate 22' which is adjustably mounted on a suitable part of the frame and such guide pin may advantageously be fitted with a roller.

The inner portion 19' of the upper edge of the shear blade and the coacting part 16' of the lower edge of the laterally projecting portion 16 of the hook plate coact in the manner of scissors blades and are sharpened accordingly, as best shown in Figure 4, the disposition of the cutting edges being such that the loops applied to the hook are not severed until they move some distance along the arm 16' from the hooked end thereof. Thus, in normal operation, one or more uncut loops normally remain on the arm of the hook plate as shown in Figure 3.

The upper edge of the shear blade 19 is stepped downwards outwardly of the cutting edge 16' thereon to form a shoulder 20 which ensures that a loop cannot move onto the cutting edge before the next succeeding loop is applied to the hook.

An angle shaped guard member 30 secured to the hook carrying member 15 has one arm thereof extending upwards with its inner face spaced from the adjacent end of said member 15 and the inner face of this arm forms a guide for the outer flattened face of the needle 18 which is normally disposed just clear of the path of movement of the hook 16'. The said inner face of the guard member 30 is however outwardly inclined at its upper end as shown at 31 (Figure 5) so that, as the needle approaches the lower end of its stroke, it is deflected inwardly if necessary—that is, away from the path of movement of the hook 16'. The outer face of the upwardly extending arm of the member 30 is engaged by the adjacent part of the shear blade 19, while the other arm of such member is adjustably secured to the member 15.

In operation the needle 18 moves downwardly through the fabric (shown at A in Figure 3) supported on the base plate whereby a loop of yarn 29 is carried through the material and below the base plate to a position somewhat below the hook 16'. As the needle commences its upward stroke, the hook plate 16 is rocked quickly towards the said needle whereby the hook 16' moves substantially into brushing contact with the outer flattened face of the needle and through the loop 29 of yarn thereon. A groove 16' on the inner face of the arm 16' of the hooked plate provides clearance for the yarn while said arm is disposed below the eye of the needle, but above the point thereof. Thus, when the needle is retracted above the base plate, the yarn remains looped around the hook and the distance of the latter below the fabric determines the length of the tufts ultimately formed. Also, as the needle is retracted, the hook plate swings outwardly away from the path of the needle and towards the opposite end of its stroke.

Thus, at each operation of the needle, a loop of yarn is applied to the hook. Now, as the hook plate moves angularly forwards towards the needle as above described, the sharpened inner portion 16' of the lower edge thereof closes on the coacting sharpened inner portion 19' of the

upper edge of the shear blade, so that the innermost loop located therebetween is severed, it being understood that the outer portion of the shear blade is guided by the pin 22 during the inward and outward movements of the hook plate. Accordingly during each normal cycle of operations, a fresh loop 29 is applied to the free end of the hook while the innermost loop is severed, one or more uncut loops being left on the hook to prevent the yarn from being pulled out when the needle is retracted.

The scissors type of severing means provides substantial advantages in manufacture, adjustment and maintenance, while the actuating means therefore are comparatively simple and readily adjusted. When it is necessary to resharpen the cutting edges of the hook plate and shear blade, these parts may be quickly removed as a single unit by removing the screw 17, and after sharpening, may be quickly and easily replaced in proper position so that no difficult or inconvenient readjustment is required.

In the modification of the invention shown in Figure 7 the hook plate carrier 15' is adjustably secured to a second spindle 32 arranged longitudinally below the shaft 10, the hook plate 16 being correspondingly longer. An actuating arm 33 secured to the shaft is bifurcated at its upper end to embrace a cam 34 on the shaft 10. One advantage of this construction is that the distance between the hook and the axis about which it oscillates is considerably greater than in the construction previously described so that the arc of movement of the hook is relatively flat and approximately parallel to the base plate of the machine. Moreover the cam 34 may be suitably shaped to impart rapid movements to the hook. A further important advantage of this modified construction is that it is applicable also to high speed sewing machines in which the shaft 10 is rotated instead of being oscillated.

In lieu of providing a second rock shaft as 32 below the shaft 10, the latter shaft may be mounted in bearings arranged somewhat below its normal position and actuated in substantially the usual way.

In the further modified construction shown in Figure 8 the hook plate carrier 15' is supported on fixed horizontal guides 35 for transverse sliding movements which are imparted thereto by a cam 37 secured to the spindle 10 which may be oscillated or rotated.

The invention has been devised primarily for incorporation in or attachment to sewing machines of ordinary types, but it will be evident that it is not confined thereto.

I claim:

1. A tuft forming sewing machine comprising a reciprocable needle spindle adapted to support a needle for carrying a loop of yarn through material to be decorated, a movable carrying member, a loop holding member detachably and adjustably secured to said carrying member, means operable to impart forward and return movements to said carrying member in timed relation with the needle spindle whereby during each such forward movement the loop holding member moves into substantial brushing contact with the needle to engage and hold the loop thereon,
2. A loop shearing member directly pivotally connected to and movable bodily by said loop holding member, coacting cutting edges on said loop holding and loop shearing members, a loop retaining shoulder on the loop shearing member and located outwardly of the cutting edge there-

on and lost motion guide means spaced from said pivotal connection for guiding said loop shearing member whereby during each forward movement of the loop holding member said coacting cutting edges move past each other to sever a loop of yarn therebetween.

2. A tuft forming sewing machine comprising a frame, a vertically reciprocable needle spindle thereon to support a needle for carrying a loop of yarn through material to be decorated, means for reciprocating said needle spindle, a base plate arranged below said needle spindle and having an aperture therein through which said needle projects during each downward stroke of the latter, a horizontally disposed spindle arranged below the base plate, means operable to oscillate said spindle in timed relation with said needle spindle, a carrying member secured to said spindle, a hook plate having a longitudinal arm detachably secured at one end to the carrying member and extending upwardly therefrom, an integral lateral arm on an upper portion of the longitudinal arm and terminating in a hook which is moved into substantial brushing contact with the needle during each forward movement of the oscillatable spindle, a laterally extending loop shearing plate directly pivotally connected to one side of the longitudinal arm of the hook plate below the said lateral arm thereon, a cutting edge forming an inner portion of the lower edge of the lateral arm, a coacting cutting edge forming an inner portion of the upper edge of the loop shearing plate, a loop retaining shoulder extending from adjacent the outer end of the cutting edge on the loop shearing plate to a downwardly stepped portion of the upper edge thereof, said shoulder being located inwardly of said hook and guide means fixed to the frame

and engaging said loop shearing plate at a position spaced from the pivotal axis thereof whereby said coacting cutting edges are caused to close together and sever a loop of yarn therebetween during each forward movement of the hook plate.

5 3. A tuft forming attachment for a sewing machine comprising a hook plate having a longitudinal arm and an integral lateral arm adjacent the upper end of the longitudinal arm and 10 terminating in a loop engaging hook, a laterally disposed shear plate arranged at one side of the hook plate, a pivotal connection between one end portion of the shear plate and the hook plate, the upper edge of said shear plate being normally disposed somewhat below the lower edge of the said lateral arm, said upper and lower edges of the shear plate and lateral arm respectively being sharpened adjacent said pivotal connection to form coacting cutting edges and a loop retaining shoulder extending from adjacent the outer end of the cutting edge on the shear plate to a downwardly stepped outer portion of the upper edge thereof.
